FUZE ARMING MECHANISM

Ralph H. Severance, Fort Wayne, Ind., assignor to The Magnavox Company, Fort Wayne, Ind., a corporation

Application August 10, 1955, Serial No. 527,614

1 Claim. (Cl. 102—79)

This invention relates generally to fuze arming mechanisms and more particularly it relates to a mechanism responsive to lineal acceleration and angular acceleration for arming fuzes in spin stabilized rockets or other projectiles of like nature.

In connection with rocket projectiles or other types of projectiles, it is conventional to stabilize their flight by the use of fins attached to the rear of the projectile, the fins acting in response to air pressure to keep the projectile on a pre-determined course. Another method of stabilizing all types of projectiles is to cause the projectile to spin during its flight. In rockets, a typical method of producing such spinning action is by directing the flow of exhaust gases at an angle to the line of flight, which causes the rocket to rotate and thereby tend to follow a pre-determined course.

Conventional fuze arming mechanisms are arranged to respond to linear acceleration of projectiles or rockets. In the case of rockets having fins, it is necessary to assume that the rockets will be stabilized by the fins and hence it is safe to arm the rocket only in response to its acceleration whereby a fuze arming mechanism responsive only to linear acceleration may be used with comparative safety, as the rocket will not be armed until it has progressed a predetermined distance along its course.

On the other hand it may be possible that a spinning type of rocket can be launched and for one reason or another it may fail to spin with sufficient angular velocity to be fully stabilized. If the rocket is not fully stabilized so that it follows its pre-determined course, then it is dangerous to arm the rocket. Accordingly, there is definite advantage in providing a fuze-arming mechanism which will arm the rocket fuze only after the rocket is launched and only after it has accelerated linearly and angularly to a pre-determined degree.

The principal object of this invention is to provide, for spinning projectiles, a fuze arming mechanism responsive to linear acceleration and angular acceleration for arming the projectile fuze only after the projectile has been accelerated linearly and angularly to a pre-determined degree.

Another object of this invention is to provide a fuze arming mechanism for spinning projectiles of such character that the force generated by linear acceleration of the projectile must attain a certain value, and the force generated by angular acceleration of the projectile must attain a certain value before the arming mechanism can operate to arm the projectile.

In accordance with this invention there is provided a fuze arming mechanism comprising a mass adapted to be mounted within a spinning type of projectile in such a way that it may move in response to a pre-determined degree of linear acceleration and in response to a pre-determined degree of angular acceleration into an arming position.

The full nature of the invention will be understood from the accompanying drawings and the following description and claim:

2

Fig. 1 is a longitudinal cross-section of a projectile embodying the fuze arming mechanism as provided in accordance with the invention.

Fig. 2 is a graph showing the relationship between 5 linear acceleration of a projectile and distance of flight of such a projectile.

Fig. 3 is a graph illustrating the relation between angular velocity of a projectile and linear distance of flight of that projectile.

10 Fig. 4 is a graph illustrating the relation of centrifugal force, existing on a body within the projectile, to distance of flight of the projectile.

Fig. 5 is a graph showing the relation of linear force exerted by a mass within the rocket in response to linear 15 acceleration and centrifugal force existing on that body, both with respect to distance of flight of the projectile.

In a typical rocket projectile there may be provided a casing 10, the nose portion of which may enclose a main explosive charge 11. To the rear of a transverse wall member 12 there may be a booster charge 14. Immediately to the rear of the booster charge there may be provided a wall member 15 having a central aperture within which is supported a lead 16 adapted to initiate ignition of the booster charge 14.

25 In accordance with this invention there is provided an arming mechanism consisting of a mass or weight member 17 pivotally mounted to casing 10 by means of a pin 18. It will be noted that the pin 18 should be located to one side of the center of gravity of weight 17. Since the 30 direction of flight of the projectile will be to the right as shown in the drawings, the pin 18 is located forwardly of the center of gravity of the weight 17.

The weight 17 may be utilized as an arming mechanism by providing a suitable conventional detonator 19 located 35 within a bore in the weight 17 as shown in Fig. 1. In its normally disarming position, the detonator 19 is disposed vertically out of contact and out of line with the lead 16. The detonator is also completely isolated from a detonator initiating mechanism 20 supported on a wall 21. The 40 details of this mechanism 20 are not shown, as they may be conventional and it will be obvious to those skilled in the art that any conventional detonator may be utilized in conjunction with this invention.

The weight 17 may be held in its normal disarming position in engagement with a stop member 22 mounted in any suitable fashion on the interior surface of casing 10. A spring 23 may be secured to weight 17 and the interior 50 surface of casing 10 normally to hold weight 17 in engagement with stop 22. The spring 23 is in the nature of a creep spring adapted to prevent any movement of weight 17 during shipment or other handling of the projectile prior to its being launched.

To the rear of the wall 21 which supports the detonator initiating mechanism 20 there is provided within casing 55 10 a rocket propulsion unit 24 in accordance with conventional practice.

In operation, it will be assumed that the rocket illustrated in Fig. 1 is of the spinning type and provided with any conventional mechanism or structure adapted to induce spinning of the rocket after it is launched. As the 60 rocket motor is started thrust is built up in the rocket and accelerates it linearly along its course. If the spin inducing mechanism, such as angularly directed nozzles, functions properly the rocket also accelerates angularly 65 or commences to spin with constantly increasing velocity. It might be noted that linear acceleration and angular acceleration endure in a rocket until the fuel in the propulsion unit is consumed. As a result, the linear velocity V and the angular velocity W increase simultaneously.

70 Fig. 2 illustrates the relationship of linear acceleration and distance of flight. Thus the curve 25 illustrates in-

creasing linear acceleration as the distance of flight increases. Since the linear acceleration increases with distance of flight, the force F exerted by the weight 17 would follow the same relation with respect to distance of flight D , as shown in Fig. 2.

In Fig. 1 of drawings, a force line F^L indicates graphically the amount of linear force on weight 17 during the initial flight of the rocket.

Fig. 3 of the drawings illustrates the relationship of angular velocity W to linear distance of flight D . The resultant curve 26 shows constantly increasing angular velocity as the linear distance of flight increases.

Fig. 4 shows the centrifugal force C existing on the weight 17, which may be calculated by the formula:

$$F = KW^2$$

Where K is a constant, F is the force shown in Fig. 2, and W is the angular velocity shown in Fig. 3. Thus it is apparent that the centrifugal force illustrated by the curve 27 increases substantially exponentially with linear distance of flight. The centrifugal force line F_c shown in Fig. 1 is therefore substantially less than the linear force during the initial flight of the projectile and hence the weight 17 maintains its normal position as shown in Fig. 1 during the initial part of the rocket's flight.

Fig. 5 shows the force curve 25 and centrifugal force curve 27 superimposed with respect to one another, and from this figure it will be apparent that the linear force due to acceleration on the weight 17 equals the centrifugal force on weight 17 at some pre-determined distance from the launching point. At other distances the linear force F is always greater or always less than the centrifugal force C . It is also apparent from Fig. 5 that the angular velocity increases at some pre-determined distance from the launcher to such a degree that the centrifugal force C exceeds the linear force F , and this is shown graphically by the force lines F^L and F'_c in Fig. 1.

Since the line F'_c is of greater length than the line F^L this indicates that the centrifugal force on weight 17 exceeds the linear force and consequently the weight rotates into dotted line position in Fig. 1, thereby aligning the detonator 19 with the detonator initiating mechanism 20 and the lead 16. When this occurs the rocket is fully armed. It should be noted that no arming can occur unless the linear force and the centrifugal force on the weight 17 have increased to a pre-determined degree as indicated in Fig. 5. Consequently the fuze-arming mechanism does not operate to arm the fuze unless the rocket

is proceeding on its course with a pre-determined linear acceleration and a pre-determined angular acceleration or velocity of spin.

While the invention has been disclosed with specific reference to a fuze arming mechanism for rockets, it will be readily apparent to those skilled in the art that the invention may also be utilized for initiating the action of any other mechanism within a spinning projectile. For example, the invention may be utilized to detonate the rocket when a pre-determined degree of spin is attained.

The invention claimed is:

In a spinning projectile, a casing having a nose portion, a detonator initiating mechanism disposed rearwardly of said nose portion, an explosive charge in said nose portion, an arming mechanism disposed between said detonator initiating mechanism and said explosive charge comprising a weight having a detonator disposed transversely thereof, a pivot pin mounted on said casing transversely thereof to the rear of said explosive charge and through said weight forwardly of the center of gravity of said weight normally to position said weight in a dis-arming position with the major portion of said weight extending to the rear of said pin, said pin supporting said weight for rotational movement between said 25 dis-arming position where said detonator is out of line with said initiating mechanism, and an arming position where said major portion extends transversely of said casing and said detonator is aligned with said initiating mechanism and said charge, a stop member fixed to said casing and extending radially inwardly thereof into engagement with said major portion, and single spring means directly connected to said casing and said weight to the rear of said pin and tensioned normally to bias said weight into engagement with said stop member with its center of gravity to the rear of said pivot pin and said detonator out of line with said initiating mechanism, whereby said weight rotates about said pivot pin from said dis-arming position to said arming position when angular acceleration of said projectile exceeds linear acceleration.
